UNITED STATES PATENT OFFICE.

WILLIAM U. GRIFFITHS, OF PHILADELPHIA, PENNSYLVANIA.

FLUSHING APPARATUS FOR WATER-CLOSETS.

1,240,197.

Specification of Letters Patent. Patented Sept. 18, 1917.

Application filed July 10, 1914. Serial No. 850,080.

To all whom it may concern:

Be it known that I, WILLIAM U. GRIFFITHS, a citizen of the United States, and a resident of Philadelphia, in the county of Philadelphia and State of Pennsylvania, have invented certain new and useful Improvements in Flushing Apparatus for Water-Closets, of which the following is a specification.

10 My invention relates to improvements in flushing apparatus for water closets and it has for one of its objects to provide an improved construction of means whereby when the valve for closing the port of the tank leading to the closet bowl is operated the valve for controlling the water supply is simultaneously opened.

15 A further object is to provide means for automatically cutting off the flow of water into the tank when the water has reached a certain predetermined height therein.

20 Other objects and advantages of my invention will be referred to in the detailed description thereof which follows or will be 25 apparent therefrom.

25 In order that my invention may be more readily and easily understood reference should be had to the accompanying drawings forming a part of this specification and 30 in which,—

Figure 1 is a front elevation of a water closet apparatus embodying my invention, the flush tank being shown, however, in vertical section;

35 Fig. 2 is a side elevation of the same;

Fig. 3 is a longitudinal vertical section on the line 3—3 of Fig. 1;

40 Fig. 4 is a transverse vertical section at right angles to the section shown in Fig. 3 and showing a detail of construction;

45 Fig. 5 is a view similar to that shown in Fig. 1 of the drawings but in which the construction is modified by the omission of the means for automatically cutting off the flow 50 of water from the supply pipe into the flush tank; and

Fig. 6 is a longitudinal sectional view of the supply pipe and the valve mechanism associated therewith for controlling the flow 55 of water therethrough into the flush tank such view being taken in a plane parallel to the view shown in Fig. 5.

Before proceeding with a detailed description of the apparatus it may be noted that 55 the constructions illustrated in Figs. 1 to 6 inclusive are adapted for use in connection

with water closets situated out of doors where the water if allowed to remain in the pipes would be frozen in cold winter weather. These constructions provide means whereby the water is allowed to drain out of those portions of the pipes which are situated above the freezing line of the earth.

Referring now to the drawings, 1 designates a closet bowl, 2 a closet seat having a 65 rearwardly extending arm 3 of any suitable known construction, and 4 a flush pipe leading from the flush tank to the bowl in the usual manner. The flush tank is designated by the reference numeral 5.

70 The rearwardly extending arm 3 is adapted to contact with the lower end of the rod 6, which may be weighted as indicated at 7. This rod extends into the flush tank 5 and has connected therewith, by a pivot 10, a 75 valve 11 which valve is adapted to open and close the port 12 communicating with the flush pipe 4. When the seat 2 is depressed the arm 3 is raised to contact with the lower end of the rod 6 to lift the same to cause the 80 valve 11 to close the port 12. When, however, the arm 3 returns to its lowermost position as indicated in Fig. 2 the rod 6 drops downwardly so that the valve 11 is open to permit whatever water may be in the tank 5 85 to be discharged therefrom. The portion of the rod 6 inside of the flush tank is provided with a projecting finger 15 which extends underneath a lever 16 provided at its outer 90 free end with a weight 17. Any other suitable means than the rod 6 may be employed intermediate the arm 3 and the valve 11 whereby movement of said arm may effect 95 the closing and opening of the valve.

In the form of construction shown in 95 Figs. 1 to 4 inclusive the end of the lever 16 opposite the weight 17 is connected at 18 to the upper end of a link 19 having pivotal connection at 20 to a projection extending outwardly from the part 21 which 100 projects upwardly from the bottom of the flush tank 5 in alignment with and in continuation of the water supply pipe 22. The lever 16 is connected intermediate its ends at 23 to the upper end 24 of a rod 25 which 105 extends downwardly in the water supply pipe 22 to a point below the frost line. The lower end of said rod is provided with a valve 26 the bottom of which is adapted to contact with the seat 27 formed in the said supply pipe to close the same to prevent the passage of water therethrough. The side

portion of the said valve when it is raised is adapted to extend over a port 28 in the side of the said pipe having connection through a pipe 29 with the soil pipe 30 leading from the closet bowl or hopper. The size of the valve is such that it may be withdrawn upwardly through the supply pipe 22 and the continuation thereof 21. 30 designates packing material held in 10 place by means of a gland 31 to prevent escape of water through the opening in 21 around the portion 24 of the rod 25.

33 designates a projection extending laterally from the part 21 and having a passage-way 34 therein in communication with the supply pipe 22. The outer portion of the lateral projection 33 is provided with an upwardly extending portion 35 which is hollow and provided with a spout 36 through which the water is discharged into the flush tank 5. The opening from the passage-way 34 in the part 33 to the spout 36 is adapted to be closed by means of a cylindrical valve 37 which may be seated 25 upon and lifted from the seat 38 by the pressure of the water against the lower or inner end thereof. The valve 37 is provided at its upper end with a flange 39 against which any water which might pass 30 upwardly around the valve would strike and thereby be prevented from projecting upwardly over the top of the flush tank.

The upwardly projecting portion 35 is provided upon opposite sides with projections 40 in which a pivot 41 is supported which pivot extends through a slot 42 in the portion 43 extending upwardly from the valve 37. The double cam member 45 is supported upon the pivot 41 and is situated in a slot 46 extending through the portion 43 at right angles to the slot 42 therein.

48 designates an arm having connection with the double acting cam 45 and the outer end of which is provided with a 45 float 49.

In operation it will be understood that when the rod 6 is raised the finger 15 thereon (shown in Fig. 1 in dotted lines) lifts the lever 16 to lift the rod 25 and open the 50 valve 26 to permit water to flow upwardly through the said valve and through the supply pipe 22 into the passage-way 34 in the part 33 and out through the spout 36 into the flush tank 5. The water continues to 55 flow into the flush tank until the float 49 is raised to a height sufficient to cause the lower part 50 of the cam 45 to contact with the upper end of the valve 37 as illustrated in Figs. 1, 3 and 4 of the drawings to force 60 the said valve 37 downwardly to close the opening from the passage-way 34 so that the flow of water into the flush tank is thereby cut off. If by any chance the means for effecting the cut-off or for closing the 65 valve 37 should not work and water in ex-

cess should flow into the tank 5 no harm would result because such excess would flow out through the over-flow pipe 51. When the rod 6 is permitted to drop the weighted lever 16 also drops to effect closing of the 70 valve 26 and thereby shut off the supply of water. As the water flows out of the tank 5 the float 49 falls or recedes so that the upper part 52 of the cam 45 contacts with the upper end of the slot 46 to raise the 75 valve 37 thereby permitting whatever water may be in the space surrounding the valve 37 to flow into the passage-way 34 and thence into the supply pipe 22, downwardly therein and out through the waste 80 pipe 39 into the soil pipe 30.

Referring now to Figs. 5 and 6 of the drawings, it may be noted that the construction in general is similar to that shown in Figs. 1 to 4 inclusive except for the omission 85 of the means acting automatically to cut off the flow of water into the flush tank. In said Figs. 5 and 6 the lever 16 is pivotally connected at 60 to a bracket arm 61 supported upon the portion 62 projecting upwardly upon the inside of the flush tank and constituting a continuation of the water supply pipe 63. The said lever 16 is slidably pivoted at 64 to a member 65 having adjustable connection with the upper enlarged end of a rod 66 the lower end of which is provided with a valve 67 of the same construction and which operates in the same way as the valve 26 illustrated in Fig. 3. The lower end of the member 65 is provided with a flange 68 for the same purpose and function as the flange 39 in Fig. 3. The portion 62, which, as stated, constitutes a continuation of the supply pipe 63, is provided with an outlet 70 from which the water is discharged from the supply pipe 63 into the flush tank 5. The flush tank in this construction is also provided with an over-flow pipe 51.

In the construction shown in these Figs. 5 and 6 when the rod 6 is lifted the finger 15 raises the lever 16 to lift the rod 66 and open the valve 67 to thereby permit water to flow through the supply pipe 63 into the flush tank 5. No means is provided in this construction for automatically cutting off the water so that so long as the rod 6 is kept in raised position the water continues to flow and if such flow continues long enough will overflow the upper end of the 115 pipe 51.

The valve 67 operates to close the opening in the waste pipe 71 in the same manner as described in connection with the valve 26 and the waste pipe 29 in Fig. 3.

In Fig. 5 the parts are shown in position with the lever 16 raised so that the valve 67 is in open position while in Fig. 6 the parts are shown in position with such valve in closed position.

I claim:—

1. In an apparatus of the character described, the combination of a flush tank, a water supply pipe having an end projecting into said tank, a valve situated in said supply pipe below the freezing line for closing the same, a rod having connection with said valve and extending therefrom through the said pipe into the said flush tank, a lever pivotally supported at one end and connected intermediate its ends to said rod and the outer swinging end of the said lever being provided with a weight, a movably supported rod extending into the said flush tank and being provided with a projection in engagement with the said lever to raise the same whereby the said valve may be opened and closed.

2. In apparatus of the character described, the combination of a pipe for supplying water to a flush tank, a valve in said pipe for closing the same, said valve being situated below the freezing line, a rod connected with said valve and extending upwardly through the said pipe into the said tank, a weighted lever pivoted at one end and having connection intermediate its ends with said valve, means for raising the said lever to open the said valve and for permitting the said lever to move downwardly to close the same, an independent valve for opening and closing a water supply passage-

way, cam means for closing the said last-mentioned valve, and means for automatically actuating the said cam.

3. In apparatus of the character described, the combination of a flush tank, a water supply pipe for supplying water to said tank, a valve for closing said pipe, said valve being situated below the freezing line, a rod connected with said valve and extending upwardly through said pipe into said tank, a lever carrying a weight at one end and pivotally supported at its opposite end, the said lever having connection intermediate its ends with the said rod, a second rod extending into said flush tank and being movably supported, the said rod having a projection thereon for raising the weighted end of said lever, a laterally extending passageway leading from the upper end of said supply pipe, a valve for closing said passage-way, and means operating to close the said valve when a predetermined amount of water has been discharged into the said flush tank.

In testimony that I claim the foregoing as my invention I have hereunto set my hand this 26th day of June, A. D. 1914.

WILLIAM U. GRIFFITHS.
